UNITED STATES PATENT OFFICE.

JAMES VAN SANT HIBBS, OF PORTLAND, OREGON.

CABINET IRONING-BOARD.

1,287,311.

Specification of Letters Patent. Patented Dec. 10, 1918.

Application filed August 31, 1917. Serial No. 189,161.

To all whom it may concern:

Be it known that I, JAMES VAN SANT HIBBS, a citizen of the United States, residing at Portland, in the county of Multnomah and State of Oregon, have invented certain new and useful Improvements in Cabinet Ironing-Boards; and I do declare the following to be a full, clear, and exact description of the invention, such as will enable others skilled in the art to which it appertains to make and use the same.

My invention relates to improvements in ironing boards, and more particularly to those which are adapted to fold into a compact space when not in use, so as to be entirely out of the way.

In attaining the desired end I employ a cabinet which is preferably built in one wall of the building, the board or boards being mounted foldably in said cabinet, one object of the invention, being to provide novel means for holding the boards in position, when extended for use, yet for permitting easy folding thereof when required.

A further object is to provide a board which is substantially balanced by weights so that after it is released, it may be folded by the touch of a finger, and similarly may be lowered with no effort whatever, this being a highly desirable feature since the housewife is caused no exertion whatever.

Another object is to construct the device in a highly efficient, yet in an inexpensive manner, and to so design the cabinet as to give the same the appearance of one of the several doors of the room in which it is located.

With the foregoing general objects in view the invention resides in the novel features of construction and unique combinations of parts to be hereinafter fully described and claimed, the descriptive matter being supplemented by the accompanying drawings which form a part of this specification and in which:

Figure 1 is a perspective view of the invention built in the wall of a room, both boards being lowered for use;

Fig. 2 is a vertical section of the invention with the two boards projected for use as in Fig. 1;

Fig. 3 is a view similar to Fig. 2 but illustrating the two boards folded in the cabinet;

Fig. 4 is a horizontal section on the plane 55 of the line 4—4 of Fig. 2;

Fig. 5 is a perspective view of one corner of the main ironing board and the relatively fixed parts coacting therewith; and

Fig. 6 is a view similar to Fig. 5 but 60 illustrating the sleeve board and its coacting parts.

In the drawings above briefly described, a cabinet 1 is shown built in one wall of a building, although this construction need 65 not be followed in all cases, since the cabinet could well be totally independent of the building and secured to the wall thereof in any preferred manner. It is highly desirable, however, to construct the cabinet when 70 building the house so that the former may be positioned out of the way by building it in the wall. The cabinet 1 includes a pair of vertical side bars 2 which may well be two of the studs of the building, if the latter be a frame structure, said bars having vertical grooves or runways 3 along their inner sides, the lower ends of said runways being preferably curved rearwardly as indicated at 4, for a purpose to be described. 80

A main ironing board 5 is normally positioned vertically in the cabinet 1 as shown clearly in Fig. 3, the rear end of said board, at the edges thereof, having laterally extending wedge shaped blocks 6 from which 85 headed studs 7 or other appropriate shoes extend laterally, said shoes being received loosely in the runways 3. When the board 5 is lowered to horizontal position, the shoes 7 travel downwardly in the runways 3 and 90 the rearwardly curved lower ends 4 of the latter, force the board rearwardly until the rear end thereof contacts with the rear side 8 of the cabinet 1. When the device is built in the wall of a building, the rear side 8 95 of the cabinet may be formed by the sheathing of the house, but when the device is built independently of the house, the wall 8 will be suitably secured to the side bars 2 of the cabinet.

U shaped seat members 9 are secured to the inner sides of the bars 2, at the lower ends of the runways 3, the opposite sides of said seat members converging downwardly so that the wedge members 6 may be snugly 100 received therein to hold the board rigidly in operative position, the contact of said board with the rear side or wall 8 of the

cabinet, also assisting in imparting the necessary rigidity to the device. Although the board is held fixedly in operative position, it is a simple matter to again raise said board or fold the same to inoperative position, since after the wedge members 6 are once freed from the seat members 9, the shoes 7 will slide freely in the runways 3. Easy operation of the device is also caused 10 by balancing weights 10, cables 11 being connected at one end to said weights and at their other ends to the necks of the headed studs or shoes 7, said cables extending over suitable pulleys or the like 12 at the upper 15 end of the cabinet and being received in the runways or grooves 3.

Pivoted at its upper end to the under side of the board 5, between the ends of the latter, is an inclined brace 13 whose lower end 20 is pivoted at 14 in the lower end of the cabinet 1, said brace folding upwardly as shown in Fig. 3, when the board is folded. It is to be observed that this brace is pivoted permanently at both of its ends so that 25 it is always in the proper relation with the parts with which it co-operates. This is a highly essential feature of the invention, since it does away with the necessity of fastening means such as those commonly used 30 on ironing board braces, and thus decreases the trouble of setting the device for operation.

For preventing the rear end of the board 5 from moving upwardly, when downward 35 pressure is exerted on the front end of said board, a suitable spring pressed latch 15 is provided, said latch being preferably mounted on the upper side of the board as shown. Since it is necessary to move the rear end 40 of the board 5, upwardly after releasing the latch 15, in order that said board may fold as intended, and since the latch must be released before this folding can take place, I preferably provide a finger ring 16 where- 45 by the latch may be released and immediately thereafter, an upward pull exerted on the rear end of the board. This detail of construction renders the device extremely easy to operate as will be apparent. The 50 latch 15 may be of such construction as to cause it to automatically spring into place when the board is lowered.

Preferably employed in connection with the features of construction above described, 55 is a sleeve board 5', the rear end of said board having outwardly extending wedge members 6' which are equipped with studs or shoes 7', the latter being received in vertical runways 3' which are formed along 60 the inner sides of a pair of vertical bars 2' secured in the cabinet between the bars 2. The wedge members 6' coact with seat members 9' at the lower ends of the runways 3', in a manner very similar to the coaction be- 65 tween the wedge members 6 and the seats 9

above described. A suitable pivoted leg 13' supports the sleeve board 5' at the required distance above the board 5, and in order to prevent upward movement of the rear end of said sleeve board, a suitable cleat 15' is 70 provided, said rear end of the board underlying said cleat when lowered.

Normally, when the device is not in use, the door of the cabinet remains closed, both boards being then folded as shown in Fig. 75 3. When the use of the boards is required, however, the door is opened and by pulling outwardly on the lower end of the board 5, the upper end thereof will be lowered, the shoes 7 then sliding downwardly in the runways 3 whose lower ends 4 force the board rearwardly until it contacts with the rear side 8 of the cabinet. This assists in holding the board rigidly in operative position, but the coaction of the wedge members 6 85 and seat members 9 when locked in engagement by the latch 15, imparts even greater rigidity to the entire device. Whenever its use is necessary the sleeve board 5' may be lowered as shown in Figs. 1 and 2 and held 90 in operative position by the cleat 15' above described.

It is to be noted that the supporting leg 13' of the sleeve board 5' rests on the main board 5. By this arrangement, the upward movement of the rear end of said main board will rock the sleeve board upwardly and rearwardly around the studs 7' so that the parts stand substantially as seen in Fig. 3, when completely folded, the sleeve board 5' resting against the main board 5. It will thus be obvious that when the board 5 is lowered, the sleeve board 5' will lower itself to operative position.

If the use of the sleeve board is not necessary it may be swung upwardly between the bars 2', but since there is danger of the board dropping when so positioned, this will seldom be done unless suitable means be provided for preventing such dropping 105. On the other hand, the sleeve board will in most cases be swung upwardly to a sufficient extent to permit its rear end to clear the cleat 15' whereupon said board will be shifted bodily upward until it may again be 110 swung downwardly without engaging the cleat. This downward swinging having been done, the rear end of the sleeve board is moved upwardly so that said board may rest vertically on a ledge or the like 15' beneath the cleat 15'. In this position, there is no danger of the sleeve board dropping accidentally.

From the foregoing, taken in connection with the drawings, it will be obvious that 125 although the invention is of simple and inexpensive construction, it will be highly efficient, durable, and easy to operate. Since probably the best results are obtained from the specific construction shown and de- 130

scribed, such construction constitutes the preferred form of the device. I wish it understood, however, that within the scope of the invention as claimed, numerous minor changes may be made without sacrificing the principal advantages.

I claim:

1. The combination of a pair of fixed horizontally spaced upwardly facing seats, an ironing board normally disposed vertically with its upper end above said seats, said board having on said upper end a pair of fixed wedges for wedging engagement with said seats when the board is positioned horizontally for use and when forced downwardly by ironing thereon, fixed vertical tracks, shoes engaging said tracks and connected to said board for guiding said wedges into said seats as the rear end of the board is lowered for use, and a support for the free end of said board when lowered.
2. A structure as specified in claim 1, said tracks having longitudinal grooves, said wedges being carried by the edges of said board, and said shoes being in the form of

studs extending laterally from said wedges and received slidably and rotatably in said grooves.

3. A device of the class described comprising a pair of parallel vertical bars having vertical runways along their inner sides and curving toward the rear edges of said bars at their lower ends, an ironing board normally positioned vertically between said bars and having shoes at its upper end slideable downwardly in said runways when said board is moved to horizontal position, said shoes and the curved ends of said runways then forcing the board rearwardly, and a fixed wall against which the rear end of said board is thus forced to rigidly hold the same in operative position.

In testimony whereof I have hereunto set my hand in the presence of two subscribing witnesses.

JAMES VAN SANT HIBBS.
